DESIGN FOR A REFRIGERATOR CABINET

Richard B. Janes, Greenville, Mich., assignor to
Gibson Electric Refrigerator Corporation,
Greenville, Mich., a corporation of Michigan

Application February 3, 1941, Serial No. 98,683

Term of patent 7 years

To all whom it may concern:

Be it known that I, Richard B. Janes, a citizen of the United States, residing at Greenville, in the county of Montcalm and State of Michigan, have invented a new, original, and ornamental Design for a Refrigerator Cabinet, of which the following is a specification, reference being had to the accompanying drawing, forming a part thereof.

In the drawing:

Fig. 1 is a perspective view of a refrigerator cabinet embodying my design; and

Fig. 2 is an enlarged top plan view of the handle area of the cabinet, partly in section, taken along the line 2—2 of Fig. 1 and in the direction of the arrows.

The right side of the cabinet is identical to the left side. The top of the cabinet is plain. The characteristic feature of the design resides in the handle area of the cabinet, as shown.

I claim:

The ornamental design for a refrigerator cabinet, as shown and described.

RICHARD B. JANES.
